UNITED STATES PATENT OFFICE

90,889

DESIGN FOR AN AMUSEMENT APPARATUS CABINET

William J. Kennedy, West Chicago, Ill., assignor of one-half to Alice J. Tierney, Chicago, Ill.

Application July 7, 1933. Serial No. 48,653

Term of patent 3½ years

To all whom it may concern:

Be it known that I, WILLIAM J. KENNEDY, a citizen of the United States, residing at West Chicago, in the county of Du Page and State of Illinois, have invented a new, original, and ornamental Design for an Amusement Apparatus Cabinet, of which the following is a specification, reference being had to the accompanying drawing, forming part thereof, and in which:

The single figure is a perspective view, of an amusement apparatus cabinet, showing my new design.

I claim:

The ornamental design for an amusement apparatus cabinet as shown.

WILLIAM J. KENNEDY.
